UNITED STATES PATENT OFFICE.

PETER J. SHRUM, OF MONACA HEIGHTS, PENNSYLVANIA, ASSIGNOR TO COLONA
MANUFACTURING COMPANY, OF PITTSBURGH, PENNSYLVANIA, A CORPO-
RATION OF PENNSYLVANIA.

DIES.

1,320,501.

Specification of Letters Patent. Patented Nov. 4, 1919.

Application filed August 20, 1918. Serial No. 250,718.

To all whom it may concern:

Be it known that I, PETER J. SHRUM, a citizen of the United States, residing at Monaca Heights, in the county of Beaver 5 and State of Pennsylvania, have invented certain new and useful Improvement in Dies, of which the following is a specification.

My invention consists of an improvement in dies for manufacturing thread protectors, 10 and has for its object to provide a pair of co-acting dies adapted to compress an annular thread protector blank between suitable receiving cavities in each die, whereby to swage over one terminal end portion of 15 the blank into rounded holding engagement with an inserted retaining abutment ring.

The dies are illustrated in the accompanying drawing in which,—

Figure 1 shows a portion of a press provided with the stationary and movable dies, 20 with the blank to be acted upon in position, in section;

Fig. 2 is a similar view showing the dies in active operation;

Fig. 3 is an enlarged sectional detail view showing the dies at the commencement of the swaging operation;

Fig. 4 is an enlarged transverse sectional view of one of the protectors before being 30 subjected to the swaging action; and

Fig. 5 shows the finished protector, after being swaged in the dies, and as applied to the threaded end of a pipe.

In the drawing, 2 represents the main 35 frame of the press, upon the base or anvil portion 3 of which is mounted the lower stationary die 4. The co-acting upper die 5 is mounted in the reciprocable power actuated head 6 of the press and is capable of being lowered upon the blank and die 4 with necessary pressure and raised therefrom by hydraulic cylinder or other mechanism, as will be readily understood.

Die 4 is provided with an annular recessed 45 cavity adapted to receive one end of the blank and is so shaped as to fixedly retain the blank and its inserted abutment ring 8 in central position and to swage the end portion of the blank inwardly around and over 50 the retaining ring, under pressure. For such purpose, the die 4 is provided with a central up-standing portion defined within the annular shoulder 9 around which the abutment ring 8 snugly fits when the blank

is lowered into operative position, as in 55 Figs. 1, 2 and 3.

The recessed portion of the die outwardly beyond the central shouldered portion is gradually dished outwardly and upwardly, as indicated at 10, beyond a comparatively 60 narrow flat portion 11. The dished portion 10 extends sufficiently far beyond shoulder 9, before terminating at the general level or top surface 12 of the die, to provide sufficient width to engage and act upon the extended end portion 13 of blank 7 independent of its outside diameter.

Thus, a blank of the thickness shown in Fig. 3 may be utilized, or the blank may be considerably thicker and of increased external diameter, as indicated in dotted lines at 70 a. With either size, or any intervening size, the gradually dished annular concaved face 10, under pressure of the upper die 5, forces the terminal metal portion 13 of the blank 75 inwardly around and partially over the retaining ring 8, as indicated at 14, Fig. 5.

Upper die 5 is likewise provided with an annular recess or groove 15 of a suitable width and depth to engage over and around 80 the upper edge of the blank so as to fixedly engage and hold it during downward pressure exerting movement of the die. With the dies as thus made, the blank with its inserted abutment ring 8, preferably snugly 85 inserted upwardly in its receiving reamed-out cavity against the root of the teeth, the pressure of the dies effects swaging over of the metal into tight holding engagement of the ring in one operation, and resulting in 90 the finished protector. The swaging operation at the same time, produces a finished rounded shoulder on the outer end of the protector, leaving it without any projecting rough edges or parts.

The construction and method of operation of the dies will be readily understood from the foregoing description, and it will also be understood that dies are to be made in different sizes to suit different sized protectors, the dies being made in sets which are easily substituted or replaced by other sizes in the same press.

Having described my invention, what I claim is:

1. In dies for making a thread protector having an inserted abutment ring and an extended outer annular portion at one end; an

integral swaging die for such portion having a central annular shoulder for the abutment ring and a surrounding gradually dished or curved swaging portion extending outwardly beyond the annular portion of the protector, and a co-acting integral pressure die adapted to engage the opposite end of the blank.

2. In dies for making a thread protector having an inserted abutment ring and an ex-

tended outer annular portion at one end; a swaging die for such portion having a central annular shoulder and a surrounding gradually dished or curved swaging portion, and a co-acting pressure die having a recessed annular portion adapted to engage the opposite end of the blank. 15

In testimony whereof I hereunto affix my signature.

PETER J. SHRUM.
